UNITED STATES PATENT OFFICE.

STEPHEN MARTINELLI, JR., OF WATSONVILLE, CALIFORNIA.

ATTACHMENT FOR BOTTLE-WASHING MACHINES.

1,130,418.

Specification of Letters Patent.

Patented Mar. 2, 1915.

Application filed June 8, 1914. Serial No. 843,773.

To all whom it may concern:

Be it known that I, STEPHEN MARTINELLI, Jr., a citizen of the United States, residing at Watsonville, in the county of 5 Santa Cruz and State of California, have invented a new and useful Improvement in Attachments for Bottle-Washing Machines, of which the following is a specification.

This invention relates to bottle washing 10 machines, and more particularly to an attachment for a bottle washing machine, and one of the principal objects of the invention is to provide an improved attachment for a well known type of bottle washing 15 machines, by means of which the rust which ordinarily collects at and adjacent to the crown groove of a bottle neck may be removed, simultaneously with the cleansing of the interior of the bottle.

Another object of the invention is to provide an attachment of the class described, affording means whereby the bottle neck 20 may be cleaned by means of rotary brushes.

Another object of the invention is to provide a device of the class described including 25 a rotary brush for cleaning the bottle neck simultaneously with the cleansing of the interior of the bottle, and means whereby the brush may be driven from the spindle of the machine.

Still another object of the invention is to provide an attachment of the class described including rotary brushes of an improved 35 nature, means for adjusting the brushes, means for attaching the brushes to a bottle washing machine, and means for driving the brushes from the spindle of the machine.

A further object is to provide a device 40 of the class described which will be simple, durable, inexpensive to manufacture, efficient in operation, and one which may be attached without the use of special tools and without the employment of skilled labor, 45 and without necessitating changes in the construction of the bottle washing machine.

With these and other objects in view which will become apparent as the description proceeds, the invention resides in the 50 construction, combination and arrangement of parts hereinafter more fully described and claimed, illustrated in the accompanying drawing, in which like characters of reference indicate like parts throughout the 55 several figures of which—

Figure 1 represents a perspective view of

the attachment showing the same in operable position on the bottle washing machine. Fig. 2 represents a top plan view of the brush holder and brushes and indicating 60 them as being in operation. Fig. 3 represents a vertical transverse sectional view taken through the brush holder, and Fig. 4 represents a top plan view of the shaft and parts carried thereby, and the arm and 65 brace for supporting the shaft. Fig. 5 represents a vertical transverse sectional view taken on a plane lying between the bridge and the driving pulley, and looking toward the former.

Referring more particularly to the drawing, 5 indicates the slide rods of a well known type of bottle washing machine, known as the "Goulding" bottle washing machine, 6 indicates the yoke carried at the 70 forward ends of the slide rods, 7 indicates the nozzle carried in fixed relation by the yoke and extending at one end forwardly of said yoke, 8 indicates the mouth piece which is carried on the front end of the 75 yoke, and 9 indicates the spindle which is driven at a high rate of speed and which carries a brush (not shown), which brush when the machine is not in the process of cleaning a bottle, is housed within nozzle 7, 80 but which is uncovered by the housing when a bottle mouth is placed against the mouth piece as indicated at Fig. 2, upon the bottle being shoved so as to move the yoke rearwardly, said brush as it is uncovered entering 85 the neck of the bottle and extending into and spreading within the bottle, and cleansing the same as the brush rotates with the spindle. The pressure upon the bottle having been relieved the yoke is carried forward by means of a spring (not shown) so that the brush is again housed within the 90 nozzle, said forward motion of the yoke withdrawing or moving the bottle from the 95 brush.

The attachment which forms the subject of this invention comprises a bridge 10 secured to cross piece 11 of the yoke, which cross piece carries the rear end of nozzle 7, by means of a screw 12, which in the usual 105 machine serves to secure a water guard over the rear end of the nozzle, which water guard is dispensed with when my improved attachment is used. One end of bridge 10 is provided with a pair of spaced ears 13, 110 between which is pivoted the lower end of an arm 14, said arm carrying at its upper

end a grease box 15 in which is journaled near its rear end a shaft 16, the forward end of which is journaled in a grease box 17 carried at the outer end of an arm 18 attached to arm 14. The rear end of shaft 16 carries 5 a disk 19, to which is secured by means of screws or other removable fastening means 20, a wood or composition or other suitable friction wheel 21, bearing upon and driven by spindle 9 as the latter rotates. The opposite end of bridge 10 from ears 13, is provided with a staple or eye 22, to which one end of a retractile spring 23 is connected, the opposite end of said spring being connected to a clip 24 provided with an opening 10 by means of which the clip may be slipped over a pin 25 carried by grease box 15, the function of the spring being to maintain the friction wheel at all times in contact with 15 the spindle, and also to take up the wear occurring in the friction wheel through constant use. Carried by the forward end of shaft 16, is a driving pulley 26 over which runs an elastic driving belt 27.

25 The brush holder comprises a sleeve 28 adapted to be slipped upon the forward end of nozzle 7 subsequently to the removal of mouth piece 8, which mouth piece may be then replaced, said sleeve being provided internally with an annular groove 29 adapted to be filled with lubricating grease, and provided further at its rear end with an annular flange 30 adapted to bear against the forward face of the yoke 6, said flange 30 co- 30 acting with a disk 31 formed on the opposite end of the sleeve, in forming a guideway for belt 27 whereby the sleeve may be rotated with the nozzle as a bearing, as the friction wheel is driven. A pair of oppositely ex- 35 tending similar forwardly curved arms 32 are formed on disk 31, and at their outer ends are provided with lugs 33 having openings 34 extending therethrough in which openings the brushes 35 are disposed. Said 40 brushes are formed of straight pieces of steel wire, at their outer ends set in a suitable knob 36 affording a finger hold for the brushes, and adapted to maintain them in fixed relation with each other, said brushes, 45 as shown, being disposed oppositely to each other, with their inner ends 37 directed toward the axis of and spaced slightly from the mouth piece 8, in position as indicated in Fig. 2 to engage the crown groove and 50 adjacent portions of a bottle neck when the bottle mouth is placed against mouth piece 8 in the initial operation of cleaning the bottle. Set screws 38 are carried by lugs 33, and are adapted to be turned into engagement 55 with the brushes 35 to maintain said brushes in fixed relation to the lugs, said screws adapted to be unloosened when the brushes wear away whereby the brushes may be advanced to take up the wear.

60 65 Through the connection of the friction

disk, the shaft pulley and elastic belt, the sleeve 28 and hence the brushes 35 are rotated at a high rate of speed relatively to the mouth piece against which the bottle mouth bears, and thus the rust accumulated in and 65 about the crown groove of the bottle neck is removed, simultaneously with the cleansing of the interior of the bottle by the brush (not shown) carried by the spindle. As before stated the yoke and parts associated therewith reciprocate longitudinally of the spindle during the operation of cleaning bottles, and as they move relatively to the spindle the friction wheel 21 slides on said spindle but it is always maintained in contact therewith so as to impart steady and uniform power to the brushes by means of the spring 23. It will be noted that brushes 35 rotate in a direction contrary to the direction of rotation of the spindle and the brush carried by said spindle, so that the tendency of the spindle brush and the brushes 35 to rotate the bottle, is counteracted by the contrary rotation of the brushes so that no extra force need be exerted by the 80 operator for maintaining the bottle in a fixed position.

The brushes 35 are disposed at an angle to each other and not in alinement with each other, and are so positioned at their inner 95 ends as to engage well within the crown groove so as to insure positive cleansing thereof.

Although I have described the preferred embodiment of my invention, I may desire 100 to make such changes in the construction, combination and arrangement of parts thereof as do not depart from the spirit of the invention and the scope of the appended 105 claims.

I claim.

1. An attachment of the class described including a bridge adapted to be secured to the yoke of a bottle washing machine, an arm pivoted at one end to one end of 110 the bridge, a grease box carried at the opposite end of the arm, a brace arm carried by said arm, said brace arm provided with a second grease box, a shaft journaled in the grease boxes, a disk carried at one end 115 of said shaft, a friction disk detachably secured to said disk, and engaging the spindle of the machine, a driving pulley carried at the opposite end of the shaft from the disk, a spring connected at one end to the 120 opposite end of the bridge from the connection point of the arm and bridge, a clip connected to said spring, means for detachably securing the clip to one of the grease boxes whereby the friction disk may be 125 maintained in constant contact with the spindle, a sleeve rotatably mounted upon the nozzle of said machine in advance of the yoke, said sleeve provided with a guideway, a driving belt carried by said driving 130

5 pulley and engaging the guideway of the sleeve, a disk formed on said sleeve, said disk provided with oppositely extending similarly curved arms, said arms provided at their outer ends with lugs, brushes extending through said lugs, means whereby the brushes may be adjusted relatively to the lugs, said brushes being oppositely disposed and adapted to engage the crown 10 groove of a bottle when the latter is placed against the mouth piece of the bottle washing machine.

2. An attachment of the class described comprising a bridge adapted to be secured 15 to the yoke of a bottle washing machine, an arm carried by said bridge, a support carried by the arm, a shaft, means carried by the arm and support for journaling the shaft, a friction disk connected with said 20 shaft and adapted to be driven by the spindle of the bottle washing machine, means for maintaining said disk in constant contact with said spindle, a pulley carried by the shaft, a sleeve rotatably mounted upon 25 the nozzle of the machine, driving means between said sleeve and pulley, and brushes supported by said sleeve and adapted to engage the crown groove of a bottle when the latter is placed against the mouth piece 30 of the bottle washing machine.

3. An attachment of the class described including a shaft, means for swingingly supporting the same relatively to the spindle of a bottle washing machine, a friction 35 drive between the spindle and shaft, means for taking up wear in the drive, a rotary brush journaled relatively to the nozzle of the machine, and a compensating drive means between the shaft and brush.

40 4. An attachment of the class described including a brush holder adapted to be journaled on the nozzle of a bottle washing machine, said holder comprising a sleeve having a groove provided therein, and hav-

ing a flange at one end adapted to bear 45 against the yoke of the machine, and a disk at the opposite end adapted to co-act with said flange in forming a guideway, arms carried by said disk, said arms being oppositely disposed and being provided with 50 lugs, brushes carried by said lugs, means whereby the brushes may be adjusted relatively to the lugs, and means for connecting the brush holder and spindle of the machine for driving said brush holder and 55 consequently the brushes in a contra-direction relative to the direction of rotation of the spindle.

5. A device of the class described comprising a brush holder adapted to be journaled adjacent the mouth piece of a bottle 60 washing machine, means for driving the brush holder, said holder including a plurality of curved arms, brushes carried by said arms and extending toward the axis of 65 the holder, said arms being so curved as to dispose said brushes at an angle to each other and directed toward the mouth piece of the machine, whereby to engage a bottle neck well within the crown groove thereof, 70 when the bottle is placed against the mouth piece.

6. An attachment of the class described comprising a brush holder adapted to be 75 journaled relatively to the mouth piece of a bottle washing machine, a shaft, means for swingingly journaling the shaft relatively to the bottle washing machine, means for driving the shaft from the spindle of the machine, means for driving the brush 80 holder from the shaft, and means for taking up wear between the shaft driving means and the spindle.
